UNITED STATES PATENT OFFICE.

PALEY KNOX RICHARDSON, OF MANGUM, OKLAHOMA.

WEANING-BIT.

1,290,355.

Specification of Letters Patent.

Patented Jan. 7, 1919.

Application filed October 31, 1917. Serial No. 199,495.

To all whom it may concern:

Be it known that I, PALEY K. RICHARDSON, a citizen of the United States, residing at Mangum, in the county of Greer and State 5 of Oklahoma, have invented certain new and useful Improvements in Weaning-Bits; and I do hereby declare the following to be a full, clear, and exact description of the invention, such as will enable others skilled in 10 the art to which it appertains to make and use the same.

This invention relates to bits to prevent sucking by colts or calves and the primary object of the invention is to provide a new 15 and improved bit of this character which will be economical to manufacture, simple in construction, efficient in operation and not liable to get out of order.

The principal use of my bit is to wean 20 colts and calves but it will be also available for use in the mouths of animals suffering from bloat or colic and a further object of the invention is to adapt the bit to such use.

With these objects in view, the invention 25 consists in the improved construction, arrangement and combination of parts hereinafter fully described and afterward specifically claimed.

In order that the construction and operation 30 thereof may be readily comprehended, I have illustrated an approved embodiment of my invention in the accompanying drawing and will now proceed to specifically describe the same in connection with such 35 drawing, in which

Figure 1 represents an elevation of the inner side of my bit, including the securing rings,

Fig. 2, a plan view of the bottom—or the 40 top—of the bit, and

Fig. 3, a sectional view on the plane indicated by the dotted line 3—3 of Fig. 2.

Like reference characters indicate the same parts in all of the figures of the drawing.

Referring particularly to the drawing, 5 indicates the body, tube, or mouth-piece of my improved bit which is curved outwardly and has integral ears 6, 6, at the ends of its 50 inner side 7 which are adapted to receive rings 8, 8, such as are used on an ordinary bridle bit and designed to receive the harness by which the bit is held in place, said ears 6, 6, being bent into the form of rings 55 9, 9, to encompass and loosely hold the rings 8, 8, in the ordinary manner.

The tubular body 5 is open from end to end and is provided with a centrally located series of holes 10 in its outer or convex side 11, and two series of holes 12, 12, in its inner 60 or concave side 7 located substantially midway between the center and the ends of the tubular body, which body is very much greater in diameter than the ordinary solid driving or riding bit for purposes herein- 65 after named.

When the bit, constructed as described, is placed in an animal's mouth, the mouth is held open and when an attempt is made to suck, wind is admitted through the outer 70 series 10 of holes and the inner holes 12, 12, or through the ends of the tubular body and the inner holes should the outer holes by any means be obstructed.

This free passage of air through the holes 75 is facilitated by their location, the forward central series 10 being removed from the locations of the gums of the animal and the ends of the tubular body projecting beyond the sides of the mouth. The air being surely 80 admitted into the interior of the body, and the inner series of holes 12, 12, being largely out of reach of the tongue, the free passage of the air through said inner holes is assured and the power of the attempt at suction by 85 the animal is destroyed.

The use of my improved bit will also greatly relieve animals affected with bloat or colic, inasmuch as the mouth is held open, the wind produced by the disease is afforded 90 a free passage outward and thrown off, the animal being prevented from retaining it by keeping its mouth open.

Making the ears 6, 6, integral with the body is economical and useful, inasmuch as 95 there is no tendency to misplace any other means of connecting the rings 8, and the expenditure of time and labor in riveting or otherwise attaching ears is dispensed with.

I have found by long experiment and use 100 that my bit, constructed as described, automatically keeps clean and is never stopped up, the small amounts of milk in attempted sucking and the water passing through the body serve to wash it out and keep it clean. 105

While I have specifically described the construction and arrangement of the parts of my bit, I do not absolutely confine myself thereto, as slight changes or variations may be made therein without departing from 110 the spirit and scope of the invention.

Having thus fully described my invention,

what I claim as new and desire to secure by Letters Patent of the United States, is:—

As an article of manufacture, a weaning bit consisting of a tubular body arcuately curved 5 throughout its length and having attaching means at its opposite ends, said tubular body being provided in its convex side at a point intermediate its ends with a series of openings, and provided in its concave side with 10 two series of openings, each series of openings on the concave side being arranged at a point intermediate the central portion of

the tubular body member and its end, all said series of openings coöperating to facilitate the free passage of air through the 15 body.

In testimony whereof I have signed my name to this specification in the presence of two subscribing witnesses.

PALEY KNOX RICHARDSON.

Witnesses:

E. E. EMBREE,
GEO. W. JOHNSON.
